UNITED STATES PATENT OFFICE.

RICHARD RUEMELIN, OF MINNEAPOLIS, MINNESOTA.

SAND SIFTER.

Application filed December 8, 1924. Serial No. 754,657.

The main object of my invention is to provide an improved form of sand sifter that will more quickly and efficiently remove dust from sand.

5 Another object is to provide means for dividing a stream of sand from which dust is to be removed into individual streams so the dust can be more readily removed therefrom.

10 Another object is to provide means for shifting or partially deflecting the individual streams of sand from side to side, so as to turn the sand over and get the dust carried in the stream, to the bottom thereof 15 where it may pass through the screen.

Another object is to provide step-offs or drops in the screen over which the sand passes so the jolt of the sand in falling over these drops will more readily remove the 20 dust therefrom.

Another object is to provide improved means for bringing the sand to be screened to the surface of the screen.

Another object is to provide quickly adjustable means for changing the angle of the screen over which the sand is passed.

With these and incidental objects in view, the invention consists of certain novel features of construction and combination of 30 parts, the essential elements of which are hereinafter described with reference to the drawing which accompanies and forms a part of this specification.

In the drawing, Figure 1 is a perspective view of my improved sand sifter. Figure 2 is a plan view of the sifting screen itself and Figure 3 is a section taken on the line 3-3 Figure 2. As shown in Figure 1, the stand 1 supports the hopper 2 and a delivery hopper 4 which tapers toward the bottom and delivers sand through a slot (not shown) to the upper end 6 of the sand screen.

This sand screen may be flat or corrugated, but I prefer to provide step-offs 7, as better shown in Figure 3, so that when the sand passes over these step-offs it will drop and jolt the dust free from the sand and let it pass more readily through the screen 8, which forms the bottom of the screen proper.

50 The sand is delivered through the slot 5 in a thin stream and passes through the channels 9 between zig-zag division strips 10 which divide the sand into individual streams and as these strips 10 are zig-zag as shown in Figures 1 and 2, the sand shifts from side

to side as it passes through these individual channels, thus turning or partially deflecting or rolling the streams of sand over and giving the dust a better chance to work free from the sand itself and pass through the 60 screen 8, and as heretofore stated, this action is further exaggerated by the step-offs 7.

It will be understood that there may be as many division strips 10 as desired, so as to make the individual streams of sand any 65 desired width.

It may be noted that the strips extend substantially the entire length of the screen frame, thus keeping the sand streams separated throughout their courses and insuring 70 a maximum utilization of the screening surface. It may be further noted, however, that it is not the primary object of zig-zagging the strips 10 to increase the lengths of the individual streams, as it may be observed 75 from the line 3-3 in Fig. 2 that the main body of the stream may follow a substantially straight path, but there is sufficient abruptness in the strip angles to merely receive the sides of the stream so as to deflect or roll 80 them over to the opposite sides, and in this way bring all the sand in contact with the fine dust removing meshes.

The screen 6 is hinged to the frame 1 at 85 11 and the posts 12 of the frame have apertures 13 therein to receive the pegs 14, thereby allowing the adjustment of the screen surface quickly and positively, so as to cause the sand to pass over the surface of the screen more or less slowly, as desired.

90 While I have described my invention and illustrated it in one particular design, I do not wish it understood that I limit myself to this construction, as it is evident that the application of the invention may be varied 95 in many ways within the scope of the following claims.

Claims:

1. In a sand sifter the combination including a normally stationary screen having an inclination of sufficient pitch to permit the sand to move downwardly thereover by gravity when such sand is fed to the upper end of the screen, and unbroken means extending longitudinally and substantially the entire length of the screen, and upon the upper surface thereof, for dividing the sand into separate parallel streams, said means being provided with laterally projecting portions for deflecting and agitating 100 105 110

ing the streams laterally as they continue downwardly over the screen from end to end thereof.

2. In a sand sifter the combination including a normally stationary screen having an inclination of sufficient pitch to permit the sand to move downwardly thereover by gravity, unbroken means extending longitudinally and substantially the entire length 10 of the screen, and upon the upper surface thereof, for dividing the sand into separate parallel streams and individually guiding the streams, said means being provided with laterally projecting portions for deflecting 15 and agitating the streams laterally as they continue downward over the screen, and means for adjusting the inclination of the screen whereby to vary the speed of sand streams thereover.
- 20 3. In a sand sifter the combination with supporting means, an inclined normally stationary screen arranged to receive sand at its upper end, unbroken zig-zag strips arranged upon the upper surface of the screen 25 and extending substantially from top to bottom thereof, for dividing the sand into streams and for laterally acting on the

streams, at intervals, as the streams pass down over the screen.

4. In a material sifter the combination 30 with supporting means, an inclined normally stationary screen adapted to receive material at its upper end, unbroken zig-zag strips arranged upon the upper surface of the screen and extending substantially from 35 top to bottom thereof, for dividing the material into separate streams and for laterally acting on the streams, at intervals, as they pass down over the screen, means for adjusting the inclination of the screen to 40 vary the gravitational material flow.

5. In a sand sifter the combination including a normally stationary screen having an inclination of sufficient pitch to permit sand to move downwardly thereover by 45 gravity, unbroken means extending longitudinally on the upper face of the screen and substantially the entire length thereof, said means being provided with laterally projecting portions to deflect and agitate 50 the sand passing over the screen, and said screen being stepped to impart jolts to the downwardly moving sand.
